US00D995210S

(12) **United States Design Patent** (10) Patent No.: **US D995,210 S**
McConnell et al. (45) Date of Patent: **** Aug. 15, 2023**

(54) **JAR ATTACHMENT FOR A BLENDER ASSEMBLY**

(71) Applicant: **WHIRLPOOL CORPORATION**,
Benton Harbor, MI (US)

(72) Inventors: **John W. McConnell**, St. Joseph, MI
(US); **Brandon T. Mock**, St. Joseph,
MI (US)

(73) Assignee: **Whirlpool Corporation**, Benton
Harbor, MI (US)

(**) Term: **15 Years**

(21) Appl. No.: **29/847,922**

(22) Filed: **Jul. 28, 2022**

Related U.S. Application Data

(60) Continuation of application No. 29/800,296, filed on Jul. 20, 2021, now Pat. No. Des. 959,910, which is a continuation of application No. 29/747,598, filed on Aug. 24, 2020, now Pat. No. Des. 925,980, which is a division of application No. 29/723,710, filed on Feb. 10, 2020, now Pat. No. Des. 898,517, which is a division of application No. 29/689,432, filed on Apr. 30, 2019, now Pat. No. Des. 874,869, which is a division of application No. 29/639,761, filed on Mar. 8, 2018, now Pat. No. Des. 852,574.

(57) **CLAIM**

We claim the ornamental design for a jar attachment for a blender assembly, as shown and described.

DESCRIPTION

FIG. 1 is a front top perspective view illustrating a jar attachment of the blender assembly of the present disclosure;

FIG. 2 is a rear top perspective view of the jar attachment of the blender assembly of FIG. 1;

FIG. 3 is a front elevational view of the jar attachment of the blender assembly of FIG. 1;

FIG. 4 is a rear elevational view of the jar attachment of the blender assembly of FIG. 1;

FIG. 5 is a first side elevational view of the jar attachment of the blender assembly of FIG. 1;

FIG. 6 is a second side elevational view of the jar attachment of the blender assembly of FIG. 1;

FIG. 7 is a top plan view of the jar attachment of the blender assembly of FIG. 1;

FIG. 8 is a bottom plan view of the jar attachment of the blender assembly of FIG. 1;

FIG. 9 is a front top perspective view illustrating a jar attachment of the blender assembly of the present disclosure;

FIG. 10 is a rear top perspective view of the jar attachment of the blender assembly of FIG. 9;

FIG. 11 is a front elevational view of the jar attachment of the blender assembly of FIG. 9;

FIG. 12 is a rear elevational view of the jar attachment of the blender assembly of FIG. 9;

FIG. 13 is a first side elevational view of the jar attachment of the blender assembly of FIG. 9;

FIG. 14 is a second side elevational view of the jar attachment of the blender assembly of FIG. 9;

FIG. 15 is a top plan view of the jar attachment of the blender assembly of FIG. 9; and,

FIG. 16 is a bottom plan view of the jar attachment of the blender assembly of FIG. 9.

The broken lines depict portions of the article that form no part of the claimed design.
